CHARGE INDUCTION

Robert W. Gundlach, Spencerport, N.Y., assignor to
Xerox Corporation, a corporation of New York
Filed Mar. 17, 1960, Ser. No. 15,704
15 Claims. (Cl. 317—262)

This invention relates in general to the field of electrostatics and in particular to the deposition of charge in xerography.

In the art of xerography, as originally conceived, it has been usual to employ a sensitive photoconductive insulating layer and expose it to a pattern of activating radiation to form a developable electrostatic charge pattern. This pattern has generally been developed on the layer itself requiring transfer of the developed image and generally cleaning of the photoconductive insulating layer prior to reuse. Techniques have recently been developed whereby charges are deposited on another surface. These techniques are described, for example, in U.S. Patents 2,221,776; 2,833,930; 2,833,648; 2,825,814; 2,912,586; 2,774,921; 2,919,967 and co-pending applications U.S. Serial No. 651,979; 633,331; 633,261; now U.S. Patents 2,934,650; 2,934,649 and 2,977,943, respectively, and 532,534. As is apparent from an examination of this reference material, these techniques of charge deposition on surfaces are dependent on certain phenomena taking place between contiguous members or surfaces. For example, in U.S. Patent 2,221,776 the principle of electron emission is relied upon for charge flow to a contiguous surface, and in U.S. Patent 2,825,814 a form of field stress is involved to form image patterns and a similar stress is involved to uniformly charge the surface in 2,833,930. Problems arise with these various prior art techniques. For example, when dealing with the concept of photoemission, it is difficult to find photoemissive layers which maintain their qualities while exposed to air, and with stress charge migration one is faced with problems of critical spacings for practical type machines and avoiding foreign materials such as dust particles from gaps in order to maintain uniform gap stresses to thus create uniform charge deposits.

These and other difficulties are overcome by the instant invention in which charge is deposited in accordance with field controls and through the use of an insulating rectifying layer. A further accomplishment of the instant invention is its ability to operate in substantially any fluid (liquid or gas) medium or in a vacuum.

It is accordingly an object of this invention to provide new improved methods of uniformly charging a surface.

It is another object of this invention to provide new and improved methods of selectively depositing electrostatic charge on a surface.

It is a further object of this invention to provide new and improved apparatus to uniformly charge a surface.

It is a still further object of this invention to provide new and improved apparatus to selectively deposit charge on a surface.

It is a still further object of this invention to devise novel means of charging in xerography.

It is a further object of this invention to devise novel and improved apparatus for image formation in xerography.

Other objects and advantages of the present invention will be more readily apparent in view of the following detailed description, especially when read in conjunction with the accompanying drawings, wherein:

FIG. 1 illustrates an embodiment of charging apparatus according to this invention;

FIG. 2 is another embodiment of charging apparatus according to this invention;

2

FIG. 3 is a still further embodiment of charging apparatus or alternatively image forming apparatus according to this invention;

FIG. 4 includes schematic diagrams of charge induction in accordance with this invention; and,

FIG. 5 is an embodiment of an automatic machine according to this invention.

For a better understanding of this invention, reference is now had to FIG. 1 wherein is shown an embodiment of charging apparatus to place a uniform charge across a surface. A chargeable member 10 is positioned on support means 11 which, in this embodiment, has edge guides 12 on support table 13. Positioned and disposed on support table 13 is motor 15 which may, for example, be electrically operated from a 110-volt A.C. power source. Extending outwardly and fixedly mounted to the housing of motor 15 is sleeve 17. Screw 16 which is directly connected to motor 15 rotates freely in sleeve 17 when motor 15 is operating. Moving sleeve 18 mounted on screw 16 includes a protruding pin or the like which extends into the helical path extending along screw 16. As screw 16 rotates, the pin protruding into the helical path in screw 16 imparts motion to sleeve 18. At the ends of screw 16 the path followed by the pin reverses the direction of sleeve 18. Attached to sleeve 18 is charging roller 20. The roller in this embodiment is spring mounted to allow positioning of chargeable members of variable thicknesses while maintaining roller 20 in contact with the upper surface of chargeable member 10. The physical connection between sleeve 18 and roller 20 is electrically insulating to electrically isolate roller 20 from sleeve 18. Roller 20 comprises an inner cylindrical electrode 21 of conductive material and an outer covering layer 22 of material having a resistivity generally in the range of from 10^5 ohm-centimeters to 10^{11} ohm-centimeters. Inner electrode 21 of roller 20 is connected to power supply 23 and support 11, which in this embodiment is conductive material, is electrically grounded.

To operate the mechanism illustrated in FIG. 1, motor 15 is energized causing screw 16 to rotate thereby imparting motion to sleeve 18 causing roller 20 to roll across the upper surface of chargeable member 10 on support 11. In the embodiment illustrated, sleeve 18 travels along screw 16 from left to right until at the right end of screw 16 sleeve 18 changes its direction of motion and returns along screw 16 from right to left. At the left end of screw 16, sleeve 18 contacts switch 25 which stops operation of motor 15, which stops rotation of screw 16 and movement of sleeve 18. Sleeve 18 thus remains at the left end of screw 16 and in a position which will not interfere with the removal or insertion of chargeable member 10 onto support 11. Further, in this position and with roller 20 out of the way, chargeable member 10 may be exposed to a pattern of activating radiation if a photoactive material. Roller 20 may be caused to move back and forth again over a chargeable member by energizing motor 15 through a switch or the like. It is to be realized that other means of causing roller 20 to roll across and create a charging field through a chargeable member, generally known to the art, are intended to be included herein and that the embodiment in FIG. 1 is for illustrative purposes only.

Reference is now had to FIG. 2 wherein another embodiment of a charging device is illustrated. In this figure chargeable member 10 is being moved between two rollers 26 and 27. As in FIG. 1, each of the rollers comprises an inner conductive electrode 21 surrounded by an outer resistive layer 22. As should be apparent, however, from FIG. 1, one of the rollers could readily

be a pure conductor (as in support 11 in FIG. 1). Rollers 26 and 27 are positioned within supports 28 and 30 and are pressed towards each other by springs 31. Electrodes 21 are electrically insulated from supports 28 and from each other by electrically insulating axle connections 32 and by chargeable member in position between the electrodes. Voltage is, in this embodiment, supplied from power supply 33 across resistance 35 having a point substantially in the electrical center grounded and, as illustrated, the voltage across the ends of the resistor is applied to the conductive portions 21 of rollers 26 and 27. There is thus applied across chargeable member 10 a charging voltage to rollers 26 and 27. Rollers 26 and 27 are mounted on supports 28 and 30 in such a manner as to freely rotate and chargeable member 10 may be moved manually therebetween, or means may be applied to the mechanism of this figure such as a motor drive or the like to cause, as through friction, chargeable member 10 to move through rollers 26 and 27 and at a controlled and uniform rate of speed.

Reference is now had to FIG. 3 wherein another embodiment of a device according to this invention is illustrated. The particular device shown in this figure is readily usable to uniformly charge a chargeable member and may be used to form image patterns of charge on the surface of a chargeable member. As shall be apparent following consideration of image formation in accordance with this figure, the devices of FIG. 1 and FIG. 2 are also readily adapted to form image patterns on, as well as to uniformly charge, a chargeable member.

Considering now the device of FIG. 3 functioning first as a charging device, a support layer 11 of conductive material is attached to a pressure plate generally designated 51 by hinges 50. Pressure plate 51 comprises a conductive layer 52 and a resistive layer 53. An insulating connecting link 55 connects handle 56 to pressure plate 51 allowing an operator to open and close pressure plate 51 away from and into contact with support layer 11. Positioned between pressure plate 51 and support layer 11 is chargeable member 10. Power supply 57 is electrically connected to conductive layer 52 of pressure plate 51 and support layer 11 is grounded. To charge a chargeable member in the device of FIG. 3, chargeable member 10 is placed on support layer 11 and pressure plate 51 is closed against the upper surface of chargeable member 10. The potential is then applied by power supply 57 creating a charging field through chargeable member 10. The potential may then be disconnected from conductive layer 52 of pressure plate 51 and pressure plate 51 raised upward so that chargeable member 10 is available to be removed from the device or to be exposed in position to an image pattern for subsequent utilization if chargeable member 10 comprises a photoactive layer.

Although in the embodiments thus far described and illustrated a chargeable member 10 has been illustrated as a single layer, it should be appreciated that chargeable member 10 may comprise a chargeable layer overlying a conductive backing layer. The conductive backing may comprise aluminum, brass, paper, foil, or the like and when present, then all of the structures illustrated in FIGS. 1, 2 and 3 can be modified to the extent that there is no need to support the chargeable member on a conductive support layer. Instead, any support material may be used, and a conductive contact to the backing member is provided to apply a potential (including ground) to the conductive backing layer and thus across an entire surface of the chargeable layer.

The chargeable member referred to in connection with this invention includes an insulating rectifying layer. Such a layer conducts readily in one direction, but blocks flow, as does an insulator, in the reverse direction. Such materials will generally preferentially conduct one polarity of charge carriers. A material is referred to as being of the p-type when the majority charge carriers are holes and n-type when the majority charge carriers are electrons. The Hall constant gives the sign of the majority charge

carrier. If the material has no preferential conductivity for either polarity of charge carriers, it may be rendered either p-type or n-type by the inclusion therein of specified impurities termed "doping" whereby it is rendered either p-type or n-type as is now well known in the transistor art. Thus, a material which is strongly p-type will conduct holes or positive charges far more readily than electrons or negative charges. Such a layer is thus a rectifying layer when joined to a material having a relatively different conductivity preference. For utility in the instant invention wherein rectification is utilized to impart an electrostatic charge to an insulating layer, photoconductive insulators which are themselves strongly p-type or strongly n-type may be used per se. As is now well known in the art, a photoconductive insulating material is an insulator in that it contains no intrinsic charge carriers, but rather possesses only those charge carriers injected therein from an external source or generated therein by the activity of activating radiation. Where the photoconductive insulating layer is insufficiently rectifying, i.e., conducts both polarities equally or is only slightly p-type or n-type, rectification may be supplied by forming a highly rectifying barrier layer between the photoconductive insulating layer and the conductive backing which injects charge carriers into the photoconductive insulator or alternatively as discussed above, the layer may be doped. As examples, zinc oxide is strongly n-type so that modification of the material either by doping or by the interposition of a barrier layer between the zinc oxide and the conductive electrode are unnecessary for utility herein. Vitreous selenium is p-type and commercial xerographic plates on an aluminum backing may be used as described herein. However, as a properly prepared selenium layer is only slightly p-type, the use of such unmodified layers results in moderately long charging times. By the addition of a rectifying barrier layer such as cuprous oxide between the vitreous selenium and the conductive backing, the charging time may be reduced to the order of 1 or 2 seconds. Alternatively, the selenium may be doped to either render it highly p-type or even to reverse the polarity of the major charge carriers to render the material n-type. Thus, as disclosed in U.S. 2,863,768, when alloyed with arsenic trisulfide, selenium becomes highly n-type while still being an effective photoconductive insulator. Tellurium is also a suitable additive to selenium to render a vitreous selenium layer n-type. The selenium may also be rendered more highly p-type by the inclusion of very minor amounts of halogen. In the case of doping with a halogen, care must be taken to prevent the inclusion of too much impurity which would render the material too conductive for use as a photoconductive insulator herein.

As should be apparent, substantially all known photoconductive insulating layers can be employed in connection with this invention, either intrinsically or as modified according to the teaching herein, and included within this group, for example, are semi-conductive materials cooled below the temperature necessary for thermal generation of charge carriers therein which thus act as insulators.

These various materials have been referred to as insulators in that each elemental area acts as controlled by fields surrounding that elemental area. Thus, no lateral flow takes place across the material. This characteristic in the layer of chargeable member 10 makes chargeable member 10 useful, for example, for a subsequent exposure if the insulating rectifying layer is photoactive so that, once sensitized, chargeable member 10 may be exposed, for example, to a light image pattern to release charge in areas exposed to light and thus dissipate charge in conformance with the light pattern leaving behind an image pattern of charge conforming to the unexposed or dark areas of a light and shadow pattern. This image pattern of charge can then be developed in accordance with known principles as, for example, as taught by the art of xerography.

Similarly, the quantity of conduction in each individual area as controlled by the fields surrounding each individual area makes the chargeable member useful in connection with forming image patterns. Image formation in accordance with this invention will be discussed below.

It is noted that insulating rectifying layers which are not light sensitive such as insulating binder layers in which the binder is opaque or photosensitive layers overcoated with an opaque layer or the like may also be used in this invention. Such layers are particularly valuable when a developable image pattern is directly induced into the layer.

The device in FIG. 3 may also be used to form charge patterns on a chargeable member. This is accomplished by positioning a selective field pattern on, for example, pressure plate 51 as by the utilization of pressure plate 51 of a xerographic plate comprising, for example, a selenium layer overlying a conductive base bearing a charge pattern on the selenium surface. The plate, in effect, comprises a conductive layer 52 and a photoconductive insulating layer 53 such as selenium. On the surface of photoconductive insulating layer 53 facing downward towards chargeable member 10 there would exist a charge pattern conforming to an image pattern to be reproduced. This pattern could have been formed on the surface using conventional xerographic techniques, through the selective deposition of charge or the selective dissipation of charge. Power supply 57 in this embodiment is then connected to apply ground potential to conductive backing 52 of plate 51. Handle 56 is attached to plate 51 as described previously or may comprise an easily attachable or detachable member. The plate, for example, is charged and exposed in an open position and handle 56 is then used to move the plate into a closed position across a chargeable member to create a charge pattern on the chargeable member. Support layer 11, as illustrated, is grounded and assuming a polarity of positive charges across the surface of xerographic plate 51, there is formed on the surface of an insulating rectifying layer (chargeable member 10) negative charges in position in areas adjacent to areas of positive charge on the surface of photoconductive insulating layer 53. The pattern on insulating rectifying layer 10 conforms in configuration to the pattern on the surface of photoconductive insulating layer 53. After plate 51 is removed, the pattern will remain in position on chargeable member 10 for subsequent utilization. The elemental area control which exists in insulating rectifying layers maintains the pattern in position and prevents its dissipation as through lateral conductivity or reverse flow. Thus, there is created following the application of selective fields through insulating rectifying layer 10, a charge pattern conforming in configuration to the field pattern applied and as described above, the field pattern may be applied using a xerographic plate bearing a charge pattern. As should be apparent, rather than using a xerographic plate as pressure plate 51, there may also be used an insulating layer at layer 53 bearing selectively deposited charges which were previously deposited in any of many known ways. For example, charges can be deposited through a scanning system or through any one of the many systems described above in the patents cited as reference material as prior techniques applied in the xerographic art. Similarly, patterns of field can be effected through the use of conductive or resistive characters surrounded by insulating material and a potential applied from power supply 57 to conductive layer 52 of pressure plate 51. The conductive or resistive characters or other pattern will selectively create fields to induce flow to the surface of chargeable member 10 conforming in configuration to the patterns present in layer 53.

It should also be appreciated that the techniques described in connection with FIG. 3 may also be used in FIG. 1 or 2 by feeding an image inducing member and an insulating rectifying layer together into the devices

and with the proper potentials applied an image pattern will form on chargeable member 10.

Reference is now had to FIGS. 4-A and 4-B wherein there is illustrated schematically charge induction of elemental areas in accordance with the invention. In FIG. 4-A charge induction is illustrated in which the charge inducing element comprises an insulating layer bearing charge and in FIG. 4-B charge induction using a roller or a platen at a fixed potential is illustrated.

Referring now to FIG. 4-A, precharged capacitor 60 comprises an elemental area of an insulating layer bearing charge and may comprise the photoconductive insulating layer of a xerographic plate or may comprise an insulating layer such as Mylar, cellophane, or the like bearing deposited charge. Variable capacitor 61 is representative of the variable air gap or other fluid gap between the charge inducing member represented by capacitor 60 and the insulating rectifying layer generally designated 62 and comprising capacitor 63 and rectifier 65. A variable capacitor 61 is included in this schematic in order to illustrate the bringing of the precharged elemental area of the charge inducing member, illustrated as capacitor 60, to and away from the surface of the insulating rectifying layer 62. As the air gap between the precharged insulator, represented as capacitor 60 and insulating rectifying layer 62 is decreased, the capacitance of capacitor 61 is increased, and as the air gap becomes extremely small due to the placing of the inducing member, represented as capacitor 60 in normal physical contact with insulating capacitor 62, the capacitance of capacitor 61 becomes relatively greater than either capacitor 60 or capacitor 63. This results in substantially all of the charge initially appearing on the lower plate of capacitor 60 now appearing on the upper plate of capacitor 61. This in turn results in charging of the lower plate of capacitor 61 with an equal amount of charge of opposite polarity. Charging of the lower plate of capacitor 61 is accomplished in this invention due to the properties of insulating rectifying layer 62 which allows charge flow in one direction and blocks charge flow in the other direction. Thus, in this instance the lower plate of capacitor 61 becomes charged negatively through a flow of charge through rectifier 65 and when the capacitance of capacitor 61 is varied to decrease the capacitance by increasing the air gap between capacitor 60 and insulating rectifying layer 62, the charge which appeared on the surface of the lower plate of capacitor 61 appears on the upper plate of capacitor 63. A balancing opposite charge appears on the lower plate of capacitor 63 attracted to this plate through ground. There thus results an elemental area of charge opposite to the charge on the inducing member, represented by capacitor 60 in this figure, on the upper surface of the rectifying insulating layer 62.

In FIG. 4-B this same concept is illustrated through the use of a roller or platen at a fixed potential. The roller or platen is illustrated as the upper plate of capacitor 61 and is connected to battery 66 which applies charge across variable capacitor 61 and insulating rectifier 62. As the capacitance of variable capacitor 61 is increased through the rolling of a roller across the surface of insulating rectifying layer 62 which decreases the air gap as the roller rolls into contact, charge will appear across variable capacitor 61 again due to the conductivity of rectifier 65 in one direction as the roller or the like is separated or rolled out of contact, the charge appearing on the lower plate of capacitor 61 will appear on the upper plate of capacitor 63 and a balancing opposite charge will be attracted to the lower plate of capacitor 63 from ground. There thus results, according to this embodiment, elemental charge induction on the surface of insulating rectifying layer 62 because of its ability to allow charge flow in one direction and its ability to prevent dissipation or retain charge once deposited on its surface.

As should be apparent in connection with FIGS. 4-A and 4-B, these schematics explain the mechanism of uniform charging of an insulating rectifying layer and similarly explain the mechanism of selective charging of an insulating rectifying layer. The controlling factor in each instance comprises the element employed to induce charge to the surface of the insulating rectifying layer. If the inducing element comprises a uniformly charged insulator or a battery potential supplied, for example through a platen, roller or conductive element, then a uniform opposite charge will deposit across the surface of the insulating rectifying layer. If, on the other hand, the inducing member comprises a surface bearing a selective charge pattern or a selective field pattern such as an insulator bearing selectively deposited charges or a conductive character or pin matrix or the like, the charges induced to the surface of the insulating rectifying layer will conform in configuration to the pattern of charges or the field pattern of the inducing member while being opposite in polarity.

Reference is now had to FIG. 5 in which is illustrated an embodiment of automatic apparatus employing the instant invention. A plate, generally designated 67, comprises a photoconductive insulating layer 68 overlying a conductive backing member 70. Plate 67, in accordance with this invention, includes an insulating rectifying layer and may comprise, for example, a selenium layer overlying a copper oxide interlayer overlying a conductive aluminum base. Such a plate member is a preferred plate of the p-type and the zinc oxide binder type plate known in xerography is a preferred n-type xerographic member. Plate 67 is driven by a motor (not shown) in the direction illustrated by the arrow and moves first through a charging station, generally designated 71, next through an exposure station, generally designated 72, and next to image induction stations, generally designated 73, then to an erase station, generally designated 75. Following erase station 75, plate 67 may be recycled again or recycling can be automatically continuous. Alternatively, the erase, charging and exposure mechanism may be placed in an inoperative condition and the apparatus run as a copier duplicator. Charging in this device is accomplished through the use of a plurality of rollers designated 76, each connected to power supply 77 and each acting to induce charge to the surface of photoconductive insulating layer 68 in accordance with the description appearing above. In effect, the application of a negative potential to rollers 76 and power supply 77 will induce, given a proper insulating rectifying layer such as selenium, a positive charge to the surface of the photoconductive insulating layer 68. Plate 67 next moves to exposure station 72 whereat an image pattern selectively activates portions of photoconductive insulating layer 68 to dissipate charge in accordance with the exposure pattern. This may be accomplished as through the use of contact light exposure mechanism or projection exposure mechanism including reflection or transmission of light from the copy to be reproduced or may alternatively be accomplished through the use of an X-ray pattern or other activating radiation pattern. Following movement of plate 67 through exposure station 72, there is in existence on the surface of photoconductive insulating layer 68 an image pattern of charge. This pattern is next moved to induction stations 73 whereat insulating rectifying layers 78 supplied from supply spools 80 are moved around rollers 81 which, as illustrated in this embodiment, are maintained at ground potential. Speed of movement of rectifying insulators 78 is synchronized with the speed of rotation of plate 67 and charge patterns are induced on the surface of rectifying insulators 78 contacting plate 67 as described, for example, in connection with FIG. 4. Rectifying insulating layers 78 may in this embodiment comprise layers of zinc oxide in an insulating binder overlying a conductive backing such as foil or paper in a conductive condition

or the like. With a positive charge pattern on the surface of plate 67, negative charge patterns conforming in configuration to the image pattern on photoconductive insulating layer 68 will be formed on the surfaces of rectifying insulators 78 at the charge induction stations 73. Following image induction while rectifying insulators 78 are in contact with the surface of photoconductive insulating layer 68, rectifying insulators 78 are moved through processing stations 82. At processing stations 82 the charge patterns on the surfaces of rectifying insulators 78 may be developed and fused to form hard copy or may be otherwise utilized as, for example, through scanning or the like to create electrical signals of the image pattern for utilization as through display on cathode ray tubes or the like. Following passage through processing stations 82 in this embodiment there is illustrated feeding of rectifying insulators 78 to take-up spools 83. As is well known in the art, these webs may be cut into proper lengths and stacked rather than fed to takeup spools as shown. In this embodiment there are illustrated two charge induction stations 73. However, it should be realized that in employing the concepts of the instant invention the original image is in no way affected or in no way deteriorated while charge is induced into an adjacent member. Accordingly, although only two stations are shown, any number of stations may be positioned around a charge inducing member or a charge inducing member may be moved into contact with an insulating rectifier to induce charge into such members substantially any number of times. Following movement of drum 67 through charge induction stations 73, the photoconductive insulating layer 68 is moved through an erase station whereat the photoconductive insulating layer may be uniformly illuminated with light to erase the charge pattern from its surface and thus prepare drum 67 for recycling. Alternatively, erasure may be omitted and drum 67 may be recycled immediately to charging station 71 whereat rollers 76 will act to charge all uncharged areas to a level of charge to create a uniformly charged plate. It should be appreciated as discussed in connection with FIG. 4 that the potential applied through rollers 76 creates a charging level which is eventually obtained during the charging step. Accordingly, if a portion of the surface to be charged is originally charged passing the entire photoconductor through the charging station will result in placing a uniform charge across the entire surface. Plate 67 is then ready for exposure for further utilization. Positioned about the device illustrated in this figure is a light tight hood or cabinet 85. In this embodiment plate 67 has been described as a light sensitive member and as such will require shielding from light during passage through the various stations as illustrated in this figure.

In all embodiments of the instant invention including both charging uniformly and charging selectively, two factors must be taken into account. First, it is essential that there be present on the charge inducing member that charge density which is desired on the surface of the insulating rectifier. If the equivalent of a battery as shown in FIG. 4-B is being employed, then the ratio of the voltage applied by the battery to that desired on the insulating rectifier is the ratio of the capacitance per unit area of the insulating rectifying layer to the capacitance per unit area of the minute air gap separating the charge inducing member and the insulating rectifier. Thus, in general, the capacitance of the air gap is much higher than the capacitance of the insulating rectifier and the potential applied by an equivalent of a battery as shown in FIG. 4-B would be less than the desired potential on the surface of the insulating rectifier. If, on the other hand, one is depositing charge in accordance with the circuit illustrated in FIG. 4-A, the capacitance of the air gap is generally much greater than that of either the charge inducing member or the insulating rectifier and accordingly need not be taken into account. Instead, the

ratio of the voltage on the charge inducing member to the voltage induced on the insulating rectifier is the ratio of the capacitance per unit area of the insulating rectifier to the capacitance per unit area of the charge inducing member. This latter example, of course, is particularly applicable in the case of inducing image patterns from an image pattern bearing insulator and the former example is, of course, particularly applicable to uniformly charging through the use of either a roller, a platen, or forming an image pattern using a shaped character to which a potential is applied, or the like. Also pertinent to the applied voltage in terms of creating a charge on the surface of the insulating rectifier is an upper limit to prevent a breakdown which is fully explored in copending U.S. patent application Serial No. 718,247, now abandoned. This upper limit is generally no problem when considering the art of xerography in accordance with known charging or image forming techniques as applied in connection with this invention.

The second factor is concerned with the time necessary for charge to be induced to the surface of an insulating rectifier. The time required for the surface to reach a potential within $1/e$ of its final value is the product of the resistivity of the material times the dielectric constant of the material both being expressed in MKS units. The resistivity, of course, is that measured in the conducting direction. Because of this factor, it is necessary to either maintain contact for an adequate time to create a situation of full charge or to provide a greater charge density in the charge inducing member and allow charge to be induced for less time as required for equilibrium to result in a charge deposit on the insulating rectifier equal to what is desired.

There are now included a few examples of operation in accordance with this invention.

Example 1

A commercial xerographic plate comprising a layer of vitreous selenium overlying an aluminum backing was uniformly charged in a commercial charging unit producing a charge potential of approximately 600 volts on the surface of the selenium layer. A commercial xerographic plate comprising zinc oxide in an insulating silicone binder overlying a paper backing was placed, in the dark, across and in contact with the selenium xerographic plate with the zinc oxide binder layer contacting the selenium layer. The zinc oxide plate was kept in contact for various times between 5 seconds and 60 seconds and was then removed in the dark and then exposed to a light pattern of an image for usual time. The zinc oxide plate was then developed in the usual way using a magnetic brush. There appeared on the surface of the zinc oxide plate an image conforming in configuration to the light image pattern.

Example 2

A commercial xerographic plate comprising a vitreous selenium layer overlying an aluminum backing member was charged and exposed in the normal manner to form an image pattern of charge on its surface. A commercial xerographic plate comprising zinc oxide in an insulating binder of silicone backed by paper was placed across the image bearing selenium plate with the zinc oxide binder layer in contact with the selenium layer. The zinc oxide binder plate was kept in contact for various times between 1 second and 60 seconds and was then removed and developed in the usual way with a magnetic brush, thus making visible on the zinc oxide binder layer the original light image pattern to which the selenium plate has been exposed.

Example 3

The steps described in Example 2 were carried out and following the positioning and separation of a zinc oxide plate across the selenium plate surface, a second zinc oxide plate similar to the one used in the first manipulation was placed across the selenium surface with the zinc

oxide layer in contact with the selenium layer and the second zinc oxide binder plate was then removed and developed forming a visible reproduction which duplicated that produced in Example 2. The same manipulation was carried out with a third and fourth zinc oxide binder plate producing duplicate developed images in each instance.

Example 4

A commercial xerographic plate comprising zinc oxide in a silicone binder overlying a paper backing was charged in a commercial charging unit and was placed with the zinc oxide binder layer in contact with a selenium layer of a xerographic plate comprising a selenium layer overlying an aluminum layer with an interface of copper oxide between the aluminum layer and the selenium layer. The selenium plate was maintained in this position for various time periods between 5 seconds and 60 seconds and was then removed and exposed and developed in the normal manner producing a developed image on the selenium layer conforming in configuration to the light image pattern.

Example 5

The same steps were carried out as described in connection with Examples 2 and 3 using as the master or inducing member a zinc oxide binder plate and using as the insulating rectifying layer the selenium layer plate structure including a copper oxide interlayer as described in Example 4, and developed images were produced on the selenium surface. The times varied between 1 second and 60 seconds.

Example 6

A roller comprising an inner conductive core and an outer resistive coating having a resistivity of about 10^7 ohm-centimeters, the resistive coating being about an inch thick, was rolled across the surface of a xerographic plate comprising a photoconductive insulating layer of vitreous selenium overlying a conductive layer of aluminum having an interface between the aluminum and selenium layer of copper oxide. Potentials between the range of -50 volts and -500 volts were applied to the conductive core of the cylindrical roller and the roller was moved at a substantially uniform rate of speed across the surface of the photoconductive insulating layer in darkness while the aluminum backing of the plate was grounded. The rate of movement of the roller across the plate was between about $\frac{1}{2}$ and 1 inch per second. The plate was then, while kept in darkness, moved to an exposure position and exposed to a light image pattern and then developed. Best results were obtained using potentials between 200 to 350 volts.

The same experiment was carried out in connection with a xerographic plate in which the photoconductive insulating layer comprising zinc oxide in an insulating binder of a silicone resin. The voltage range in this instance was between 50 volts and 500 volts. The plate was then exposed and developed in a normal manner to produce a visible image of the light image pattern.

In the case of the selenium photoconductive insulating layer, the voltage applied to the cylindrical core was negative in polarity and the developer material included negatively charged toner, and the image developed included toner depositions in areas of shadow in the light and shadow pattern to which the plate was exposed. In the case of the zinc oxide insulating binder photoconductive layer, the core of the roller was connected to a positive potential and the developer toner was positively charged and the developed image included developer material deposited in areas not exposed or in shadow areas of the light and shadow pattern to which the image pattern was exposed.

As should be apparent, charging in accordance with this invention is dependent on field applied through a material which conducts in one direction and blocks in

the reverse direction. Accordingly, the inducing member could comprise a conductive layer positioned closely adjacent to the surface of the insulating rectifying layer. However, since defects in the surface of the insulating rectifying layer would result in a discharge which would remove substantially the field from other areas, it is desired to use in a platen, as for example, shown in FIG. 3, or on rollers, as for example shown in FIGS. 1 and 2, a resistive layer including a material having a resistivity above about 10^5 ohm-centimeters in order to prevent rapid charge flow through defects and to continue a uniform field across the insulating rectifying layer.

Also, as should be apparent in connection with the examples above, variations in capacitance will result in a variation in the applied potential or the created charge as previously discussed.

There have been given a number of examples of operation in accordance with this invention. These examples, plus the discussion of the invention in connection with the drawings, will suggest obvious modifications and variations to those skilled in the art, and such variations and modifications are intended to be included within the scope of this invention, and it is intended to cover the invention broadly within the scope of the appended claims.

I claim:

1. The method of charging a plate including an insulating rectifying layer capable of allowing flow of current in a first direction and sufficiently insulating in the reverse direction to retain charge on a surface thereof comprising, applying to said plate a field having a direction to cause current flow in said first direction, and then removing the applied field trapping charge on the surface of said rectifying insulating layer thereby producing a field across said plate opposite in direction to the applied field.

2. The method of uniformly charging a plate including an insulating rectifying layer capable of allowing flow of current in a first direction and sufficiently insulating in the reverse direction to retain charge on a surface thereof comprising, in the absence of light, applying to said plate a uniform field having a direction to cause current flow in said first direction, and then removing the applied field trapping charge on a surface of said insulating rectifying layer thereby producing a field across said plate opposite in direction to the applied field.

3. The method of claim 2 in which said plate includes a layer of vitreous selenium and in which the field is applied to cause deposition of positive polarity charges across an external surface of said vitreous selenium layer.

4. The method of claim 2 in which said plate includes a layer of zinc oxide in an insulating binder and in which said field is applied to cause deposition of negative polarity charges across an external surface of the zinc oxide binder layer.

5. The method of claim 2 in which said uniform field is applied by rolling a roller electrode at a substantially uniform speed across the plate member.

6. The method of claim 2 in which said uniform field is applied by positioning a platen electrode across the area of the plate to be charged and by maintaining said electrode in position for a sufficient period of time to create a desired amount of charge on the plate member.

7. The method of claim 2 in which said uniform field is applied by positioning a charged insulating layer across

a surface of said plate and by maintaining the insulating layer in position for a sufficient time period to create a desired amount of charge on the plate member.

5 8. The method of claim 7 in which said insulating layer comprises the photoconductive insulating layer of a xerographic plate which has been uniformly charged with corona charge.

10 9. The method of selectively depositing charge on the surface of a plate including an insulating rectifying layer capable of allowing flow of current in a first direction and sufficiently insulating in the reverse direction to retain charge on a surface thereof comprising, applying to said plate an electrostatic field in image configuration having a direction to cause current flow in said first direction, and then removing the applied field trapping charge in image configuration on a surface of said insulating rectifying layer thereby producing a field across said plate opposite in direction to the applied field.

15 10. The method of claim 9 in which said plate includes a layer of vitreous selenium and in which the field is applied to create an image pattern of positive polarity charges on an external surface of the vitreous selenium layer.

20 11. The method of claim 9 in which said plate includes a layer of zinc oxide in an insulating binder and in which said field is applied to create an image pattern of negative polarity charges on an external surface of the zinc oxide binder layer.

25 12. The method of claim 9 in which the field in image pattern is applied by positioning across the surface of said plate an insulating layer bearing charges in image configuration.

30 13. The method of claim 9 in which the field in image pattern is applied by applying a potential to an electrode member comprising areas of conductive and insulating material varying in accordance with an image pattern to be reproduced.

35 14. The method of claim 11 in which said insulating layer comprises the photoconductive insulating layer of a xerographic plate having an image thereon formed by sensitizing said xerographic plate and exposing said xerographic plate to an image pattern.

40 15. The method of depositing charge on a layer member at least capable of current flow in a first direction comprising positioning said member in an electrostatic field to cause current flow in said first direction through said member and in the absence of light exposure of said member, and then trapping charge on said member while said member is sufficiently insulating in the reverse direction to said first direction and removing said applied field from said member thereby producing across said layer member a field opposite in direction to said applied field.
